UNITED STATES PATENT OFFICE

GEORGE A. MACREADY, OF LOS ANGELES, CALIFORNIA

MUD GUARD FOR CORE DRILLS

Application filed March 14, 1929, Serial No. 346,955. Renewed November 23, 1932.

My invention relates to a simple, new and improved apparatus for preventing chunks of mud, cavings or débris from entering and obstructing the core receiving barrel of a core drill during the operation of lowering it into a hole.

In the operation of core drilling it is usually necessary to lower the core drill down the hole each time a core is desired. In core

drilling in some oil regions, such as California, formations are often soft and cavy, holes may deviate from vertical, and mud laden fluid is used in the hole. In ordinary practice the lower end of the core receiving

barrel is open and is usually the most advanced portion of the core drill. When a core drill is lowered into a hole it naturally slides along the lower side of the hole if the hole is not exactly vertical and pushes a pile of scrapings, cavings, débris and mud chunks ahead of it. This débris accumulates directly in front of the mouth of the core receiving

barrel. If the core barrel is open or provided with a check valve communicating with the drill pipe above then a portion of the fluid entering the lowering drill pipe can enter it through the core barrel as well as through the conventional circulation ports. This condition creates an upward current in

the core receiving barrel which carries chunks of débris up into the core receiving barrel. The larger chunks may not be able to pass the opening at the upper end of the barrel and are trapped to block the barrel.

In extreme cases the upper end of the core receiving barrel may become so tightly plugged that the fluid pushed ahead of the incoming core has no exit with the result that the core is prevented from entering the barrel and recovery reduced. Even when core recovery is not reduced the presence of débris in the core receiving barrel is undesirable because of contamination of the core.

From the foregoing remarks it will be readily understood that a means of preventing débris accumulating in the core receiving barrel will be very useful.

An object of my invention is to provide a closure which will partially close the lower

end of the core receiving barrel during lowering into a hole sufficiently to exclude chunks of débris but be open enough to allow liquid to enter the barrel to relieve pressures and also to provide means on the closure to permit ready installation and permit its removal from the entrance of the core receiving barrel when coring is commenced.

With the foregoing and other objects in view which will be made manifest in the following detailed description and especially pointed out in the appended claims, reference is had to the accompanying drawing for illustrative embodiment of the invention, wherein:

Figure 1 is an elevation of my invention showing it installed in the mouth of a core receiving barrel, the latter being partially shown in section;

Figure 2 is another elevation of my invention but viewed from a direction at right angles to the last;

Figure 3 is a cross section of my invention at the mark 3—3, viewed looking down; and,

Figure 4 is an elevation of a modified form of my invention for use in core barrels provided with barbed retaining means and is shown in installed position, the core barrel being partially shown in section.

Similar numerals refer to similar parts throughout the several views.

In the accompanying drawing the body of the mud guard, designated as 1, is a piece approximately five diameters in length, preferably of hard wood although other materials can be used. The lower end of the piece 1 is preferably provided with a blunt conical point 2 suitable to deflect chunks of débris aside. Slightly above the lower end

2 is an upwardly facing projection 3 extending out beyond the lower end 9 of the core receiving barrel 10. This projection can be made in the form of a transverse piece of wood or other material 7 inserted through a hole in body 1, or it may be turned on the body as a one-piece construction such as the projection 3a on body 1a in the modified form shown on Figure 4.

Above the projection 3 I provide spring barbs such as barbs 4 which may be attached

to the body 1 by tacks 5 or other suitable means as shown in Figure 1, or such as barbs 4a attached to the core retaining device 8a of core drill 10a as illustrated in Figure 4. 5 The barbs can best be made of strips of thin sheet metal, 20 gauge galvanized sheet iron being found very satisfactory.

Co-operating with the barbs is any convenient shoulder as shoulder 6 on the 10 interior wall of the core retainer 8 of core barrel 10 co-operating with barbs 4, or as shoulder 6a on body 1a co-operating with barbs 4a of the core retainer 8a. The form shown in Figure 1 has a shoulder 6b so that it 15 can be used on either form of core retainer. The shoulder 6a or 6b can be turned directly on body 1 or 1a or it can be formed by a metal collar attached to the body.

The purpose of the co-operating barbs and 20 shoulder is to prevent the mud guard falling out of the core drill during lowering into the hole, and to permit free upward movement of the mud guard in the core barrel ahead of the incoming core. The mud guard should be 25 preferably made to have a specific gravity of between 1.500 and 2.000 (referred to water= 1.000) so that it will not be so light as to float to the top of the core barrel ahead of the core or on the other hand be so heavy as to 30 crush the core. This is easily accomplished by selection of materials.

The form shown in Figure 1 can be used 35 in core drills having either barbed or shoulder retaining devices. The form shown in Figure 4 is for use in core drills provided with barbed retainers. For use in core drills having shouldered retainers the shoulder 6b can be dispensed with.

The installation of my invention is very 40 simple. I first inspect the barbs to see that they spread sufficiently to engage the shoulder. I next insert the upper end of the body in the mouth of the core receiving barrel and apply pressure, say of my hand, to the lower 45 pointed end and push the mud guard into the barrel until the projection 3 touches the lower end 9 of the core drill. The mud guard is thus installed and the barbs engage the shoulder to prevent it falling out.

50 The underground operation is also very simple. As soon as the core drill enters the liquid standing in the hole the liquid can enter to fill the core barrel through space 11 between the mud guard and the core receiving barrel but this space is too narrow to admit large chunks of débris which are deflected aside by the pointed end of the mud guard. The core drill is lowered until point 2 touches the bottom of the hole and then the weight of 55 the core drill etc. comes on the projection 3 shearing or breaking it off and forcing the mud guard into the core receiving barrel. Coring then proceeds with the mud guard resting lightly on the top of the core. When 60 the core drill is brought to the surface with

its core the mud guard is removed from the barrel so that no injurious material is left in the hole. The form shown in Figure 1 is so easily repaired that it can be used for numerous cores before discarding.

70 It will be understood that various changes in detail of construction may be made without departing from the spirit or scope of the invention as defined by the appended claims.

75 I claim as my invention:

1. A mud guard for core drills comprising a body provided with a lateral projection thereon, a shoulder on said body facing said projection, and resilient barbs attached to said body between said projection and said shoulder projecting from said body and pointing in the direction of said projection.

80 2. A mud guard for a core drill comprising a wooden stick and resilient metal strips each attached at one end to said stick and having their free ends normally urged away from said stick to a width greater than the bore of said drill but yieldable to contract to a width less than the bore of said drill.

85 In testimony whereof I have signed my name to this specification.

90 GEORGE A. MACREADY.
